UNITED STATES PATENT OFFICE.

CLAUDE LESLIE FREELAND, OF BRISTOW, OKLAHOMA.

PROCESS OF AND APPARATUS FOR CONDENSING, TREATING, AND WASHING HYDRO-CARBON VAPORS.

Application filed September 9, 1921. Serial No. 499,464.

My invention relates to processes and apparatus for condensing, treating and washing hydro-carbon vapors, and the purpose of my invention is the provision of a process 5 and an apparatus for condensing crude oil vapors.

I will describe one process and one form of apparatus, each embodying my invention, and will then point out the novel features 10 thereof in claims.

In the accompanying drawings:—

Figure 1 is a view showing in perspective one form of apparatus embodying my invention,

15 Figure 2 is a vertical longitudinal sectional view of the apparatus shown in Figure 1,

Figure 3 is a vertical sectional view taken on the line 3—3 of Figure 2.

20 Referring specifically to the drawings in which similar reference characters refer to similar parts, T designates a condensing tube of any suitable length having an entrance end 15 communicating with a pipe

25 P for supplying crude oil vapor to the tube. The discharge end 16 of the tube carries a collar P' and in which is slidably fitted for longitudinal adjustment a collecting pipe P² that extends into the tube in the manner shown in Figure 2. The pipe P² may be 30 locked in any longitudinally adjusted position by means of a packing gland 17 which can be screwed down hard enough to firmly lock the adjustable pipe.

35 For introducing water into the tube T, I provide pipes W and W' which extend into the tank at a point adjacent the entrance end 15 and have right angularly disposed branch portions 20 and 21, respectively, 40 which are disposed in spaced relation to the inner wall of the tube in the manner clearly shown in Figure 2. The branch pipes 20 and 21 are perforated at intervals as indicated at 20^a and 21^a respectively, so as to 45 effect the discharge of water therefrom in the form of fine streams, the arrangement being such as to force the water at right angles to the tube length and cause a rotary circulation of the water therein.

50 This rotary circulation or whirling motion of the water is in the direction of the discharge end 16 of the tube and is such as to form at the axis of the whirl an opening which coincides with the longitudinal axis 55 of the tube T and consequently with the

pipes P and P', and it is on the inner surface of this whirling body of water, that the major condensation of vapor occurs. The introduction of the vapor into the vortex of the water performs the important 60 function of washing the vapor so that a clean product results. The water is finally discharged from the tube through the pipe W² into any suitable settling tank (not shown), there being a very small amount of 65 water to be disposed of.

It is also a purpose of the invention to treat the condensate as it is formed, and for this purpose, a tank 22 is mounted in any suitable manner to communicate with the 70 tube T, so that variable portions of a chemical C (for example, caustic soda) in the tank, may be caused to drip into the water, mingle therewith and produce its action on the condensate. It is unnecessary to give 75 more than the one example of the chemical to be employed, it being sufficient to say that any one of a number of chemicals is suitable for the purpose.

80 In the operation of the condenser, it is adapted to be used in conjunction with a refining apparatus such as that embodied in my co-pending application filed Oct. 10, 1919, Serial No. 329,725, Patent No. 1,516, 85 285 with the pipe P constituting a continuation of the vapor discharge pipe of the refining apparatus so that the fuel vapor discharged from the apparatus is conveyed under pressure, because of a prior heating, 90 axially into the tube T. As the vapor enters the entrance end of the tube, it passes into the opening at the vortex of the whirling body of water and finally finds its way into the pipe P². During its passage 95 through the vortex the cooling properties of the water effects a condensation of the vapors so that when reaching the collecting pipe P² they flow off in the form of liquid. For instance, if gasoline vapor is to be 100 condensed, gasoline vapor is introduced and the cooling by water condenses the vapor to gasoline, and in like manner, when benzine vapor or other volatile oil vapors are used, each retains its identity in a refined form.

105 The diameter of the collecting pipe P² is the same or greater than the diameter of the vortex so that a collection of the condensed vapors can be readily effected without collecting an appreciable amount of water. There is no vapor at the inlet of the collect- 110

ing pipe; merely liquid. The liquid being lighter than water goes through the collecting pipe to the practical exclusion of water.

It is to be particularly noted that the tube 5 T is of uniform internal diameter through the major part of its length (see Figure 2), thereafter flaring substantially as shown for the purpose of permitting an increase in the diameter of the vortex. This feature in conjunction with the longitudinal adjustment 10 of the collecting pipe P^2 permits of the condensation and collection of various grades of fuel vapors. For example, by adjusting the collecting pipe rearwardly toward the 15 discharge end 16 from the position shown in Figure 2, its entrance end intercepts the condensed vapors.

The entrance end of the collecting pipe P^2 is positioned at a point within the passageway along the axis of the vortex where the end meets the crest between the straight and widest parts of the passageway or bore shown in Figure 2. In this position the condensate is gathered without skimming an 25 undesirable amount of the water. It is only necessary that the vapor contact the wall of fluid in the passageway in order to cause condensation. The condensate will not mix with the cooling water to any appreciable 30 degree.

From the foregoing operation it will be manifest that my apparatus involves a process of condensing hydro-carbon vapors which consists in introducing water into a 35 tube so as to create a whirling movement of the water about the longitudinal axis of the tube and in such manner that it travels longitudinally thereof to form an axial opening of increasing diameter that provides a passageway into which said vapors are introduced, and that during travel of the vapors through the passageway they are subjected to the cooling action of the water to effect a condensation of the same. Furthermore, the 45 process includes the collecting of the condensed vapors in the vortex and at various points along its length to allow of the collecting of condensed fuel vapors of different grades.

50 Although I have herein shown and described only one process and one form of apparatus for condensing and collecting fuel vapors, it is to be understood that various changes and modifications may be made herein without departing from the spirit of the invention or the spirit and scope of the appended claims.

What I claim is:—

1. An apparatus for condensing hydro- 55 carbon vapors comprising a tube, pipes arranged within the tube having outlets so located as to force water into the tube at right angles to the tube length and cause a

rotary circulation of the water therein, a pipe for supplying hydro-carbon vapors to 65 the axis of the tube to pass through a hollow passageway formed by the whirling body of water without mingling therewith, and a collecting pipe extending into the tube and adapted to collect the condensed 70 vapors from the axis of said whirl.

2. An apparatus of the character specified comprising a tube, means for spraying water into the tube so as to impart to the water a whirling movement spirally of the 75 axis of the tube, means at one end of the tube for introducing hydro-carbon vapors into a hollow passageway formed by the whirling water, and means at the opposite end of the tube and disposed axially thereof for collecting the condensed vapors.

3. An apparatus of the character specified comprising a tube, means for spraying water into the tube so as to impart to the water a whirling movement spirally of the 85 axis of the tube, means at one end of the tube for introducing hydro-carbon vapors into a hollow passageway formed by the whirling water, and means at the opposite 90 end of the tube and disposed axially thereof for collecting the condensed vapors, said last mentioned means being adjustable longitudinally of the tube for the purpose described.

4. An apparatus of the character de- 95 scribed comprising a tube having an entrance end and a discharge end, said tube having a portion increasing in diameter toward the discharge end, pipes extending into the tube adjacent the entrance end thereof 100 and having branches disposed longitudinally within the tube and formed with perforations arranged to discharge a cooling liquid so as to import to the cooling liquid a whirling motion spirally and longitudinally of the axis of the tube, a pipe at the entrance end of the tube for introducing hydro-carbon vapors into a hollow passageway formed by the whirling liquid, and a collecting pipe 105 at the discharge end of the tube arranged to collect the condensate from said passageway, said collecting pipe being adjustable longitudinally of the tube for the purpose described.

5. Apparatus for condensing hydrocarbon 115 vapors comprising a container, means to introduce liquid into the container so that it takes a spiral course along the container forming a passageway, means for introducing vapor at one end of the container to contact with the surface of the passageway but not mingle with the liquid, and means for conducting the resulting condensate out of the other end of the container.
